CLAIM

The ornamental design for a portion of a shoe upper, as shown and described.

DESCRIPTION

FIG. 1 is a side elevational view of one side of a portion of a shoe upper showing my new design;

FIG. 2 is a side elevational view of the other thereof;

FIG. 3 is a front elevational view thereof;

FIG. 4 is a rear elevational view thereof; and,

FIG. 5 is a top plan view thereof.

The broken line showing the shoe sole and the disclaimed portion of the shoe upper in FIGS. 1—5 is for illustrative purposes and forms no part of the claimed design.
